UNITED STATES PATENT OFFICE.

CHARLES BENSO AND JOHN MERKEL, OF MINNEAPOLIS, MINNESOTA.

BOWLING-ALLEY.

SPECIFICATION forming part of Letters Patent No. 367,130, dated July 26, 1887.

Application filed October 8, 1886. Serial No. 215,661. (No model.)

To all whom it may concern:

Be it known that we, CHARLES BENSO and JOHN MERKEL, of Minneapolis, in the county of Hennepin and State of Minnesota, have invented certain new and useful Improvements in Bowling-Alleys, of which the following is a specification.

Our invention relates to an improvement in bowling-alleys; and it consists, generally, in the construction and combination hereinafter described, and particularly pointed out in the claims.

In the drawings which form a part of this specification, Figure 1 is a plan view of a bowling-alley which embodies our improvement. Fig. 2 is a plan view, enlarged, of the ball-projecting device. Fig. 3 is a longitudinal section of the same on line *x x*, Fig. 2; and Fig. 4 is a cross-section of the same, taken on line *y y*, Fig. 2.

2 represents the platform or floor of the alley, at one end of which the ten pins are placed. At the opposite end the ball-projecting device is located. This consists of a bed-plate, 3, which is attached to the alley by a pin or pivot, 5, located at or near the center and upon the under side of the bed-plate 3, and to which it is permanently attached. A socket, 7, is secured to the alley and receives the pin 5, which 25 may be held in place by means of a washer and nut attached to the screw-threaded end of the said pin. In the rear of the pin 5 and socket 7, and also attached to the floor of the alley, we place a flanged nut, 9, whose interior opening 30 is screw-threaded and receives the bolt or set-screw 10, which passes through the slotted opening 11 in the bed-plate, and is provided with a head, 12, which bears upon the said bed-plate as the screw is turned, and clamps it 35 in any desired position. A pin or handle, 13, is preferably attached to the head for convenience of operation.

15 is a hollow plunger held in bearings 16 and 17, located upon the bed-plate 3. The outer end, 18, of this plunger is preferably enlarged and slightly rounded upon the surface which comes in contact with the ball. The plunger 15 is provided with lugs or projections 19, which engage springs 20, located in 40 the hanger 16, which act as cushions and relieve the shock as the plunger is operated. The plunger may be provided with a suitable

rib or projection, 21, that may fit into a suitable recess in one of the hangers, for the purpose of preventing the plunger from turning 55 on its axis.

23 is a standard which forms the abutment for the actuating-spring 25, which extends into the plunger and forms a bearing upon it near its outer extremity, as shown in Fig. 3. 60 A pin, 22, may be attached to the standard 23, and extend into the spring to hold the outer end of said spring in place upon the standard.

27 is a lever which extends over the top of the plunger, and is attached to the bed-plate 65 by means of a spring-fulcrum, 28. This spring-fulcrum consists, preferably, of a central hub, 29, to which the lever 27 is secured. This hub is attached to a central shaft, 30, which forms a bearing in a suitable casing attached to the 70 bed-plate. Located in this casing is a volute spring, 31, one end of which is attached to the casing, and the other end to the shaft 30. The tension of the spring is exerted upon the shaft to revolve it and throw the lever 27 forward to 75 the position shown in Fig. 1 and in dotted lines in Fig. 2.

A post, 33, may be placed upon the under side of the lever 27, with a roller, 34, upon its lower extremity, which travels upon the bed-plate and supports the weight of the lever and prevents it from resting upon or coming in contact with the plunger 15. We prefer to place a roller, 34, upon the top of the plunger, the axis of which is secured to the said plunger, against which the lever 27 comes in contact and retracts the plunger. A lug or projection upon the plunger may serve the same purpose; but the friction upon the lever will be obviated by the use of the roll. 90

37 represents an inclined projection or latch upon the plunger at or near its rear extremity, which is arranged to operate and interlock with a spring-catch, 39. The catch is thrown out of contact with the projection 37 by means 95 of the lever 40, suitably fulcrumed upon the catch-support. The outer end of this lever may be provided with a rod, 41, terminating in a button, 42, by which the lever may be operated when the device is inclosed, as may 100 sometimes be considered advisable.

The operation is as follows: The lever 27 is drawn back and in its movement comes in contact with the roll 35 upon the plunger 15. The

said plunger is retracted against the tension of the spring 25 until the projection 37 on the said plunger passes the spring-catch 39, which is forced out in front of the said projection, and holds the plunger in its retracted position. The lever 27 is then released and is immediately carried back to its original position by the action of the spring 31, as shown in dotted lines in Fig. 2, so that it will be entirely out of the way, and will not interfere with the further operation of the plunger. The ball may now be placed in position and the bed-plate may be turned so as to aim the device at any desired point in the alley. When this is done, the set-screw 10 may be operated by turning the handle 13, and the bed-plate secured in the desired position. The lever 40 is now operated by pressing the button 42. This throws out the spring-catch 39 and releases the plunger, which is forced forward by the action of the spring 25, and the ball is projected down the alley by the force of the said spring and in the direction previously determined. When the plunger has exerted its force upon the ball and has nearly reached the end of its stroke, the lugs 19 upon its sides come in contact with the springs 20 located in the hangers 16. These springs receive the force of the concussion and

are compressed, and thus relieve the hanger of the sudden blow which it would otherwise receive. 30

We claim as our invention—

1. In a device of the class described, the combination, with the pivoted bed-plate provided with a clamping device, of the spring- 35 actuated plunger, the retracting-lever provided with the spring 31, and the spring-catch 39 for holding said plunger in a retracted position, all substantially as described.

2. The combination, with the spring-actuated plunger 15, having the lugs 19, of the standard 16, having the cushion-springs 20, the spring-catch, and the retracting-lever 27, all substantially as described. 40

3. The combination, with the spring-actuated plunger, of the pivoted lever 27, provided with the spring 31, substantially as described, and for the purpose set forth. 45

In testimony whereof we have hereunto set our hands this 29th day of September, 1886.

CHARLES BENSO.
JOHN MERKEL.

In presence of—
R. H. SANFORD,
A. M. GASKELL.
